PUSH BUTTON ELEVATOR CONTROL
SYSTEM

Harry Benjamin Goldman, Pittsburgh, Pa.

Application July 20, 1932, Serial No. 623,495

21 Claims. (Cl. 187—29)

My invention relates to pushbutton control systems for electric elevators, and it has particular relation to certain hereinafter-mentioned improvements which, while not limited to any particular use, are primarily and especially adapted for hold-down or constant-pressure pushbutton control systems in which the pushbutton must be pressed down constantly as long as the elevator is to run. By the term "elevator" I mean to include a vertically moving cage, car or platform for freight, passenger or dumb-waiter use.

One of the objects of my invention is to provide a non-interference switch adapted for a constant-pressure pushbutton control-system for elevators, in order to safeguard the persons using the elevators, so as to give them time to load and unload. According to my invention, the non-interference switch-contacts are in series with the landing pushbuttons, as in my pending application Serial No. 408,932, filed November 22, 1929, for Automatic elevator controls. These switch-contacts are opened whenever the elevator motor is energized, but first they are shunted by an auxiliary contact-device which was not provided in my pending application above-mentioned. The shunt-connected auxiliary contact-device keeps the landing pushbuttons live so that a constant-pressure control system may be used. As soon as the elevator-motor is de-energized, the auxiliary contact-device instantly opens, and the non-interference switch begins to close, being retarded by a dash-pot or the like, meanwhile "killing" the landing pushbutton and giving the operator time to load or unload, or time to open a guard-device which automatically locks out the elevator-motor controls.

Another object of my invention is to provide a non-interference switch which is mechanically interlocked with the reversing contactors of an electric elevator system of the constant pressure pushbutton type.

A further object of my invention is to provide an elevator control system utilizing barriers or guard-devices, the opening of which will lock out the elevator motor so that the elevator-car cannot be moved until the barrier is manually closed, supplemented by means of automatically ringing an alarm whenever someone depresses a button at another landing when the barrier at the elevator-car has been left open, so that the operator at the car-landing will close the barrier again.

With the foregoing and other objects in view, my invention consists in the elements, combina-

tions, systems and methods hereinafter described and claimed, and illustrated in the accompanying drawing, wherein

Figure 1 is a simplified diagrammatic view of circuits and apparatus illustrating a preferred form of embodiment of my invention, and

Figs. 2 and 3 are similar views showing modifications.

An elevator car is raised and lowered by a reversible electric motor 2, shown as a three-phase induction motor, which is controlled by two main "up" and "down" electromagnetic reversing contactors U and D for energizing it in either direction of rotation. The acceleration of the motor, on starting, may be controlled by two starting resistances 5, which may be cut out by an accelerating relay 6 energized from a timing relay 7. The motor may be stopped by the usual brake, as shown, for example, in my aforementioned pending application.

Each of the reversing contactors U and D has an energizing coil 8, two main contacts 9 for the motor circuit, a normally open auxiliary contact 11, and preferably also a normally closed auxiliary contact 12, although the latter may be omitted if the contactors are provided, as is common, with electrical or mechanical interlocks for preventing the simultaneous actuation of both contactors, as indicated at 13.

Current is supplied to the contactor-coils 8 from the supply-line 15 through a switch 16 having an auxiliary contact 17 for the contactor-coil circuit. An overspeed switch 18 on the motor shaft is also included in the contactor-coil circuit, as well as a final "up" limit switch 19, a final "down" limit switch 20, a car-gate contact 21 and a car safety switch 22.

One of the supply-leads 23 of the contactor-coil circuit is connected to a control-means in the car, preferably one which cannot be moved to the "up" and "down" positions at the same time, being either a car switch or mechanically interlocked "up" and "down" pushbuttons 24 and 25, preferably having a mechanical interlock 26 for preventing both buttons from being depressed at the same time.

In the normal "at rest" position of the control-means 24 and 25 in the car, a circuit is completed to a landing-pushbutton supply-lead 27 leading to a plurality of "up" and "down" landing pushbuttons 29 and 30, each landing having one "up" pushbutton and one "down" pushbutton.

The "up" pushbuttons 24 and 29 in the car and at the landings, when depressed, connect the supply-lead 23 to an "up" conductor 31 which leads

to the electromagnet-coil 8 of the "up" contactor U, through an "up" stop limit switch 32. The "down" pushbuttons 25 and 30, when depressed, connect the supply-lead 23 to a "down" conductor 33 which leads to the electromagnet-coil 8 of the "down" contactor D, through a "down" stop limit switch 34. The car pushbuttons 24 and 25 are so arranged that, when either one is actuated, the landing-pushbutton supply-lead 27 is deenergized, as shown.

The arrangement just described is what I call a "constant-pressure" or "hold-down" pushbutton control, in which the "up" or "down" contactor U or D, which energizes the motor 2, is held closed only as long as the pushbutton is held down. Such constant-pressure control systems, lacking the automatic control features which are provided for some elevators, are inherently less expensive than the automatic systems, and every effort must be made to keep down the expense by using the simplest possible control circuit and apparatus.

As pointed out in my above-mentioned automatic elevator control case, Serial No. 408,982, it is desirable to provide a non-interference switch to "kill" the landing pushbuttons for a few seconds after the car stops, so as to prevent anyone else from "interfering" with the operator's control over the car before he has time to enter or leave the car or to operate a door or barrier such as the above-mentioned car-gate contact 21 which opens and thus "kills" all control over the elevator-motor.

When an effort is made to apply a non-interference switch to a constant-pressure elevator control, difficulty is involved because of the necessity for keeping the landing pushbuttons 29 and 30 live until the motor stops, because the motor cannot be kept going if the pushbutton circuit is interrupted. Furthermore, economic considerations, as above pointed out, lead to a desire for as few relays as possible, even avoiding the necessity for the electromagnetic or relay-type of non-interference switch which is shown in my above-mentioned pending application.

In view of the foregoing considerations, I have devised a mechanical non-interference switch 36 and I have shunted its contacts 37 by means of the normally open auxiliary contacts 11 on the reversing contactors U and D. When the normally closed contacts 12 are utilized, the normally open contact 11 of each contactor is connected in series with the normally closed contact 12 of the other contactor, so that there can be no possibility of erroneous operation.

The non-interference switch-contacts 37 are connected in series with the landing-pushbutton supply-lead 27.

The non-interference switch 36 is operated by means of a mechanical connection 40 to the two reversing contactors U and D, preferably including resilient connections or springs 41, 42, carried by the respective contactors, so that, when either contactor is raised or energized, it lifts the non-interference switch 36 and opens the contacts 37. The mechanical connection is such, however, that before the contacts 37 are opened the normally open auxiliary contact 11 of the actuated contactor is closed, so that a shunting circuit is made around the contacts 37 in order to avoid even a momentary break in the pushbutton circuit. This is an important precaution in a constant-pressure pushbutton system, as above described.

The non-interference switch 36 is provided

with a dashpot 44 or equivalent time-delay device for retarding its action, and this device may retard the switch more strongly when it is closing than when it is opening, as indicated by the inclination of the piston-packing in the drawing. 80

When the energized reversing contactor U or D is deenergized, it immediately drops, thus permitting the non-interference switch to begin to drop, moving slowly on account of the dashpot. However, the auxiliary contact 11, which was closed when the contactor was energized, is immediately opened, so that the landing-pushbutton-circuit is opened during the time required for the non-interference switch-contact 37 to close, thereby safeguarding the operator as previously described. 85

It is noted that my use of a mechanical non-interference switch, instead of an electromagnetic non-interference relay, may be applied to automatic, as well as constant-pressure, pushbutton control systems. 90

In addition to, or instead of, the car-gate contact 21 already mentioned, I prefer to use landing doors or barriers, carrying switches or contacts 50 which are all connected in series, so that the elevator cannot be operated unless all barriers are properly closed, and I also desire to provide signal means that will operate, without any additional wiring or equipment, (so as to cut down expense), whenever a landing pushbutton 105 29 or 30 is depressed, to summon the elevator car, when one or more of the barriers or doors are open.

To this end, I provide a door-contact relay 52 which performs the double function of placing a 110 "break" in the "up" and "down" contactor-coil circuits, when one door or barrier is open, and transferring the energizing circuit from the "up" or "down" contactor-coil 8 to a bell or other signal 54, when one door or barrier is open. 115

The door-contact or barrier-contact relay 52 is provided with an actuating coil 53 which is energized whenever all of the door contacts 50 are closed. This causes the relay to pick up, closing two normally open contacts 55 and 56 which are 120 in series with the "up" and "down" conductors 31 and 33, respectively, for the two contactor-coils 8, and at the same time opening two normally closed contacts 57 and 58 which are connected between the bell or signal device 54 and 125 said "up" and "down" conductors 31 and 33, respectively.

When the door-contact relay 52 is not properly energized, the "up" and "down" conductors 31 and 33 are thus caused to actuate the bell 54, instead of actuating the contactor-coils 8, so that when a pushbutton is depressed under these circumstances the bell automatically rings, thus summoning the person who left the door open, so that he will close the door and permit someone 135 else to use the elevator.

The signal-arrangement just described is usually applied on a freight-elevator or dumb-waiter installation, where one bell somewhere in the shaftway will suffice for all landings. However, 140 I am not limited to any particular number of bells.

When my signal device is applied to either freight or passenger elevators, I prefer to provide, for the protection of the operator in the car, an emergency-release switch 59 in the car, which must be held down to be effective, and which will short-circuit all of the door contacts and keep the operator from being "stuck" between two landings. 145 150

It will be noted that my double-purpose door-contact and signal relay 52 not only avoids the use of extra equipment for signalling purposes, but it also avoids the necessity for a separate circuit for the sole purpose of signalling, which, under union regulations, could not be installed by the elevator workmen, but must be installed by electricians, and, according to some safety codes, must use wires lying in separate conduits. All of these difficulties, as well as improved automatic and instantaneous signal-service, are obtained by my relay 52 which avoids the necessity for a separate signalling pushbutton at each landing.

While I have shown and described my invention in a preferred form of embodiment, I do not desire to be limited altogether thereto. For example, in dumb-waiters, the control equipment 24 and 25 in the car would be omitted, as well as the car-gate contact 21 and the car safety switch 22. The foregoing and other changes can be made without departing from the essential spirit of my invention. I desire, therefore, that my appended claims shall be accorded the broadest interpretation consistent with their language and the prior art.

As another exemplary modification, it may sometimes be desirable to provide landing pushbuttons so arranged that, if the car is at the top 30 of its shaftway, and two or more "down" buttons are pressed at different landings at the same time, the car will stop at the last button reached, when it is released, regardless of how the "down" buttons are actuated at higher landings, and if the 35 car is in the basement and two or more "up" buttons are pressed at different landings at the same time, the car will stop when the lowest button is released, instead of keeping on traveling until the last "up" landing button is released, as 40 in Fig. 1.

For this purpose, I may provide long-stroke, double-contact "up" and "down" buttons 61 and 62 at the landings, as shown in Fig. 2, connecting them so that the energizing current, after passing through the non-interference switch 37, is led first to the top and bottom contacts of one of the buttons, as 62, at the lowest landing, then from the top contacts of this button to the top and bottom contacts of the other button 61 at the same landing, then from the top contacts of the last-mentioned button to the top and bottom contacts of one of the buttons of the next higher landing, and so on through all the landing buttons. The bottom contacts of the "down" buttons 62 at the landings lead to the "down" conductor 33 which supplies the "down" contactor as in Fig. 1, while the bottom contacts of the "up" buttons 61 at the landings, in Fig. 2, lead to the "up" conductor 31. Long-stroke buttons 61 and 62 will have to be used to provide time, after a button 61 or 62 has been released, for the main "up" and "down" contactor, as the case may be, to drop down, thereby open-circuiting the auxiliary non-interference contacts 11 and "killing" all of the landing buttons before the top contacts of the released button are closed so as to energize the buttons at the higher landings.

If it is desired to have the elevator stop at the first "down" button that is reached on descending in response to a call from a plurality of landing buttons, instead of continuing on to the bottom one, as in Fig. 2, I may utilize the connections shown in Fig. 3, wherein the supply current coming from the non-interference switch 37 goes first to the "up" button 61 at the lowest landing, and

thence on through the other "up" buttons 61, in order, as indicated at 71, while a branch circuit 72 leads from the non-interference switch 37 and goes first to the "down" button 62 at the top landing, and thence on through the other "down" buttons 62, in order, as indicated at 73.

I claim as my invention:

1. A pushbutton elevator-control system; comprising, in combination with an elevator car and a reversible electric elevator motor; electromagnetic "up" and "down" reversing contactors, energizing means for the energizing coils of said reversing contactors, said energizing means comprising a source of supply and control circuits including pushbuttons at the landings; a delayed-action non-interference switch having contacts in series with the energizing circuits for said landing pushbuttons, means responsive to the energization of either of said reversing contactors for first closing a by-pass circuit around said non-interference switch-contacts and then causing said non-interference switch-contacts to open, and for responding to the deenergization of the energized contactor for opening said by-pass circuit and then causing said non-interference switch-contacts to close only after a predetermined time-delay.

2. A pushbutton elevator-control system; comprising, in combination with an elevator car and a reversible electric elevator motor; electromagnetic "up" and "down" reversing contactors having energizing coils, main contacts for the elevator motor circuit, a normally closed auxiliary contact and a normally open auxiliary contact; energizing means for the energizing coils of said reversing contactors, said energizing means comprising control circuits including pushbuttons at the landings and control means in the car; and non-interference means for giving the user of the elevator time to enter or leave the car after it has reached its landing before anyone else can summon the car from another landing; characterized by said non-interference means comprising a delayed-action relay having normally closed contacts which open after a slight delay when either of said reversing contactors is actuated and which close after a longer delay when the actuated contactor is released, said delayed-action relay-contacts being in series with the landing bushbuttons and being shunted by the normally closed auxiliary contact of the "up" contactor in series with the normally open auxiliary contact of the "down" contactor, and being also shunted by the normally open auxiliary contact of the "up" contactor in series with the normally closed auxiliary contact of the "down" contactor.

3. A constant-pressure pushbutton elevator-control system; comprising, in combination with an elevator car and a reversible electric elevator motor; electromagnetic "up" and "down" reversing contactors; control means in the car for energizing either of said reversing contactors at will and for instantly discontinuing the energization thereof upon the return of said control means to its normal inoperative position; and constant-pressure "up" and "down" pushbuttons at the landings for energizing said "up" and "down" contactors, respectively, while one of said pushbuttons is being held down; characterized by having a retarded non-interference switch having contacts in series with the energizing circuits for said landing pushbuttons, means responsive to the energization of either of said reversing contactors for first closing a by-pass circuit around said non-interference switch-contacts and

- then causing said non-interference switch-contacts to open, and for responding to the deenergization of the energized contactor for opening said by-pass circuit and then causing said non-interference switch-contacts to close only after a predetermined time-delay. 5
4. A pushbutton elevator-control system; comprising, in combination with an elevator car and a reversible electric elevator motor; electromagnetic "up" and "down" reversing contactors having energizing coils, main contacts for the elevator motor circuit, and a normally open auxiliary contact; energizing means for the energizing coils of said reversing contactors, said energizing means comprising control circuits including pushbuttons at the landings, a retarded non-interference switch having contacts in series with the energizing circuits for said landing pushbuttons, connections for connecting each of the normally open auxiliary contacts of the two reversing contactors in parallel to said non-interference switch, means responsive to the energization of either of said reversing contactors for causing said non-interference switch-contacts to open 10 after the closure of one of said shunting auxiliary contacts, and means responsive to the deenergization of the energized contactor for causing said non-interference switch-contacts to close only after a predetermined time-delay. 15
5. A pushbutton control-system for an electric elevator comprising a car, barriers for the safeguarding of people, and barrier-operated switches for the prevention of elevator-movement when said barriers are not properly positioned, characterized by electromagnetic "up" and "down" reversing contactors; "up" and "down" pushbuttons at the landings for energizing said "up" and "down" contactors, respectively; and a retarded non-interference switch having contacts in series with the energizing circuits for said landing pushbuttons, means responsive to the energization of either of said reversing contactors for first closing a by-pass circuit around said non-interference switch-contacts and then causing said non-interference switch-contacts to open, and for responding to the deenergization of the energized contactor for opening said by-pass circuit and then causing said non-interference switch-contacts to close only after a predetermined time-delay sufficient for the person in control of the elevator to operate one of said barriers. 20
6. The invention as specified in claim 5, characterized by a barrier-contact relay having an energizing coil in series with a plurality of said barrier-operated switches, whereby said barrier-contact relay is energized only when said serially connected barrier-operated switches are all closed, said barrier-contact relay having normally open contacts connected in series with an energizing circuit of both of the reversing contactors, so as to prevent the operation of either contactor when one or more of the barriers are improperly positioned, and signal means connected to be effectively energized in lieu of the "up" or "down" reversing contactor when a pushbutton is depressed while the barrier-contact relay is deenergized. 25
7. The invention as specified in claim 5, characterized by a barrier-contact relay having an energizing coil in series with a plurality of said barrier-operated switches, whereby said barrier-contact relay is energized only when said serially connected barrier-operated switches are all closed, said barrier-contact relay having a pair of normally open main contact circuits connected 30
- in series with the respective energizing circuits of the "up" and "down" reversing contactors, and a signal means, said barrier-contact relay having a pair of auxiliary contact circuits which are closed when said barrier-contact relay is unenergized, for completing an energizing circuit from the "up" and "down" pushbutton circuits to said signal means to energize the latter whenever a pushbutton is depressed when one of said serially connected barrier-operated switches is open. 35
8. A pushbutton control-system for an electric elevator comprising a car, barriers for the safeguarding of people, and barrier-operated switches for the prevention of elevator-movement when said barriers are not properly positioned, characterized by electromagnetic "up" and "down" reversing contactors; "up" and "down" pushbuttons at the landings for energizing said "up" and "down" contactors, respectively; a barrier-contact relay having an energizing coil in series with a plurality of said barrier-operated switches, whereby said barrier-contact relay is energized only when said serially connected barrier-operated switches are all closed, said barrier-contact relay having a pair of normally open main contact circuits connected in series with the respective energizing circuits of the "up" and "down" reversing contactors, and a signal means, said barrier-contact relay having a pair of auxiliary contact circuits which are closed when said barrier-contact relay is unenergized, for completing an energizing circuit from the "up" and "down" pushbutton circuits to said signal means to energize the latter whenever a pushbutton is depressed when one of said serially connected barrier-operated switches is open. 40
9. A pushbutton control-system for an electric elevator comprising a car, barriers for the safeguarding of people, and barrier-operated switches for the prevention of elevator-movement when said barriers are not properly positioned; characterized by electromagnetic "up" and "down" reversing contactors; "up" and "down" pushbuttons at the landings for energizing said "up" and "down" contactors, respectively; a signal means; and means responsive to an open position of one or more barrier-switches for making an energizing circuit connection from one or more landing pushbuttons to said signal means. 45
10. A pushbutton control-system for an electric elevator comprising a car, barriers for the safeguarding of people, and barrier-operated switches for the prevention of elevator-movement when said barriers are not properly positioned; characterized by electromagnetic "up" and "down" reversing contactors having energizing coils, energizing means for the energizing coils of said reversing contactors, said energizing means comprising control circuits including pushbuttons at the landings, and a retarded non-interference switch having contacts in series with the energizing circuits for said landing pushbuttons, means responsive to the energization of either of said reversing contactors for first closing a by-pass circuit around said non-interference switch-contacts and then causing said non-interference switch-contacts to open, and for responding to the deenergization of the energized contactor for opening said by-pass circuit and then causing said non-interference switch-contacts to close only after a predetermined time-delay sufficient for the person in control of the elevator to operate one of said barriers. 50
11. The invention as specified in claim 10, characterized by a barrier-contact relay having an 55

- energizing coil in series with a plurality of said barrier-operated switches, whereby said barrier-contact relay is energized only when said serially connected barrier-operated switches are all closed, said barrier-contact relay having normally open contacts connected in series with an energizing circuit of both of the reversing contactors, so as to prevent the operation of either contactor when one or more of the barriers are improperly positioned, and signal means connected to be effectively energized in lieu of the "up" or "down" reversing contactor when a pushbutton is depressed while the barrier-contact relay is deenergized. 10
12. The invention as specified in claim 10, characterized by a barrier-contact relay having an energizing coil in series with a plurality of said barrier-operated switches, whereby said barrier-contact relay is energized only when said serially connected barrier-operated switches are all closed, said barrier-contact relay having a pair of normally open main contact circuits connected in series with the respective energizing circuits of the "up" and "down" reversing contactors, and a signal means, said barrier-contact relay having a pair of auxiliary contact circuits which are closed when said barrier-contact relay is unenergized, for completing an energizing circuit from the "up" and "down" pushbutton circuits to said signal means to energize the latter whenever a pushbutton is depressed when one of said serially connected barrier-operated switches is open. 20
13. A pushbutton control-system for an electric elevator comprising a car, barriers for the safeguarding of people, and barrier-operated switches for the prevention of elevator-movement when said barriers are not properly positioned; characterized by electromagnetic "up" and "down" reversing contactors having energizing coils; energizing means for the energizing coils of said reversing contactors, said energizing means comprising control circuits including pushbuttons at the landings; a barrier-contact relay having an energizing coil in series with a plurality of said barrier-operated switches, whereby said barrier-contact relay is energized only when said serially connected barrier-operated switches are all closed, said barrier-contact relay having a pair of normally open main contact circuits connected in series with the respective energizing circuits of the "up" and "down" reversing contactors, and a signal means, said barrier-contact relay having a pair of auxiliary contact circuits which are closed when said barrier-contact relay is unenergized, for completing an energizing circuit from the "up" and "down" pushbutton circuits to said signal means to energize the latter whenever a pushbutton is depressed when one of said serially connected barrier-operated switches is open. 30
14. A pushbutton control-system for an electric elevator comprising a car, barriers for the safeguarding of people, and means including barrier-operated switches for the prevention of elevator-movement when said barriers are not properly positioned; characterized by means, including electromagnetic "up" and "down" reversing contactors having energizing coils, for controlling the operation of the car; energizing means for the energizing coils of said reversing contactors, said energizing means comprising control circuits including pushbuttons at the landings; a signal means, and means responsive to an open position of one or more barrier-switches for making an energizing circuit from one or more landing pushbuttons to said signal means. 40
15. The invention as specified in claim 4, characterized by a mechanical connection between said non-interference switch and the reversing contactors whereby said non-interference switch is lifted whenever either one of the reversing contactors is lifted into energized position. 50
16. A pushbutton elevator-control system; comprising, in combination with an elevator car and a reversible electric elevator motor; electromagnetic "up" and "down" reversing contactors, energizing means for the energizing coils of said reversing contactors, said energizing means comprising control circuits including pushbuttons at the landings; a delayed-action non-interference switch having contacts in series with the energizing circuits for said landing pushbuttons, means for actuating said non-interference switch when either of the reversing contactors is energized, to open its contacts, whenever one of the reversing contactors is energized, and quick-acting means for shunting said non-interference switch contacts when either of the reversing contactors is energized. 60
17. A pushbutton elevator-control system; comprising, in combination with an elevator car and a reversible electric elevator motor; electromagnetic "up" and "down" reversing contactors, energizing means for the energizing coils of said reversing contactors, said energizing means comprising control circuits including pushbuttons at the landings; a retarded non-interference switch having contacts in series with the energizing circuits for said landing pushbuttons, a resilient mechanical connection between said non-interference switch and the reversing contactors whereby said non-interference switch is lifted whenever either one of the reversing contactors is lifted into energized position, and a time-delay device for retarding the lowering of said non-interference switch upon the deenergization of the energized contactor, and quick-acting means for shunting said non-interference switch contacts when either of the reversing contactors is energized. 70
18. A pushbutton control-system for an electric elevator comprising a car, barriers for the safeguarding of people, and barrier-operated switches for the prevention of elevator-movement when said barriers are not properly positioned, characterized by electromagnetic "up" and "down" reversing contactors having energizing coils, main contacts for the elevator motor circuit, and a normally open auxiliary contact; energizing means for the energizing coils of said reversing contactors, said energizing means comprising control circuits including pushbuttons at the landings, a retarded non-interference switch having contacts in series with the energizing circuits for said landing pushbuttons, a mechanical connection between said non-interference switch and the reversing contactors whereby said non-interference switch is lifted whenever either one of the reversing contactors is lifted into energized position, a dashpot for retarding the lowering of said non-interference switch upon the deenergization of the energized contactor, and connections for connecting each of the normally open auxiliary contacts of the two reversing contactors in parallel to said non-interference switch. 80
19. The invention as specified in claim 1, characterized by long-stroke, double-contact "down" buttons at the several landings, connected in parallel to said non-interference switch. 90

series with each other, in order, and long-stroke double-contact "up" buttons at the several landings, connected in series with each other, in order, whereby, upon the simultaneous depression of 5 two "up" landing buttons, or two "down" landing buttons, the car is under the control of the button closest to the source of supply.

20. A constant-pressure pushbutton electric control system for elevators comprising "up" and 10 "down" control-circuit means, a supply circuit therefor, double-contact "up" buttons at the several landings, energized from said supply circuit in series with each other, in order, for energizing said "up" control-circuit means when an "up" 15 button is depressed, and double-contact "down" buttons at the several landings, energized from said supply circuit in series with each other, in order, for energizing said "down" control-circuit means when a "down" button is depressed, whereby, upon the simultaneous depression of two "up" 20 landing buttons, or two "down" landing buttons,

the car is under the control of the button closest to the source of supply.

21. A constant-pressure pushbutton electric control system for elevators comprising "up" and "down" control-circuit means, a supply circuit 80 therefor, double-contact "up" buttons at the several landings, energized from said supply circuit in series with each other, in order, starting with the lowest landing, for energizing said "up" control-circuit means when an "up" button is depressed, and double-contact "down" buttons at the several landings, energized from said supply circuit in series with each other, in order, starting with the top landing, for energizing said "down" control-circuit means when a "down" button is depressed, whereby upon the simultaneous depression of two "up" landing buttons, or two "down" landing buttons, the car is under the control of the button closest to the source of supply. 95
